AXEL JOHNSON, OF OAKLAND, CALIFORNIA, ASSIGNOR TO AMERICAN CAN COMPANY, OF SAN FRANCISCO, CALIFORNIA, A CORPORATION OF NEW JERSEY.

APPARATUS FOR APPLYING RING-LINERS TO CAN ENDS.

1,299,188.

Specification of Letters Patent.

Patented Apr. 1, 1919.

Application filed January 4, 1916. Serial No. 70,226.

To all whom it may concern:

Be it known that I, AXEL JOHNSON, a citizen of the United States, residing at Oakland, in the county of Alameda and State of California, have invented certain new and useful Improvements in Apparatus for Applying Ring-Liners to Can Ends, of which the following is a specification.

The present invention relates to can making machinery, and more particularly to an apparatus for applying ring liners to can ends.

Machines for this purpose, as at present constructed, are of the intermittent type, in which a can end is advanced by a series of step movements, and a ring liner applied thereto during a period of rest. This involves the intermittent operation, and the starting and stopping of a large number of parts in the machine, some of which have considerable weight, and a consequent loss of power ensues, as well as unavoidable wear and tear.

The object of the present invention, therefore, is to provide a machine for the described purpose in which the can ends are continuously moved along by a conveyer, and ring liners successively deposited thereon, while said ends are moving. The result of this continuous operation is greatly increased speed, capacity, and smoothness of operation, with the expenditure of less power.

In order to comprehend the invention, reference should be had to the accompanying sheets of drawings, in which—

Figure 1 is a plan view of the machine, a portion of the casing being broken away to show the interior working parts.

Fig. 2 is a vertical longitudinal section through the center of the machine, taken in the direction of the arrows on the line $x-x$ of Fig. 1 of the drawings.

Fig. 3 is a vertical transverse section, taken in the direction of the arrows on the line $y-y$ of Fig. 1 of the drawings.

Fig. 4 is a fragmental vertical section taken in the direction of the arrows in the line $z-z$ of Fig. 3 of the drawings, showing the driving mechanism.

Fig. 5 is a detailed perspective view, enlarged, of the ring liner holder and a por-

tion of the turret, certain parts being broken away for the sake of clearness.

Fig. 6 is a detailed perspective view of a positioned can end, a ring liner, and a plunger for applying the same, the parts being separated to show their relative positions.

In the drawings, and referring more particularly to Figs. 1 and 2 thereof, the numeral 1 represents a suitably constructed supporting frame or bed having a laterally extending bracket 2, and supporting a horizontal table 3. A semi-cylindrical casing or drum 4, supported by a vertical circular end plate 4', Fig. 3 of the drawings, rests upon the table 3, and has within it an axially disposed shaft 5, extending from and fixed to a central hub 4" in said end plate 4'. Journaled for rotation upon said shaft 5 is a turret 6, having a cylindrical rim 6', of such size as to closely fit but yet freely rotate within the drum 4. A thrust collar 7 retains said turret upon the shaft 5. 75

A transverse drive shaft 8, Figs. 1, 2, 3 and 4 of the drawings, is suitably journaled in the frame 1, and is provided with means, as, for example, a belt pulley 9, for receiving power from an outside source, not shown in the drawings. Said drive shaft 8 carries a gear 10, which drives the turret 6 by means of a train of intermeshing gears 11 and 12, Figs. 2 and 4 of the drawings, and a series of gear teeth 14 cut in the periphery of said turret 6, Figs. 1, 3, 4 and 5 of the drawings. 85

The turret rim 6' is provided interiorly with a series of inwardly projecting bosses 15, Figs. 2, 3 and 5 of the drawings, opposite each of which there is an opening 16 90 in the web of the turret 6. A seat or recess for receiving and conveying the ring liner, preferably a circular groove 17, the exact diameter of the ring liners to be applied, is cut into the exterior face of the rim 6' over 95 each boss 15, and extended down thereinto, and centrally of each of said circular grooves 17 a hole 18 is formed through each boss 15. A ring 19 lies within each circular groove 17, said ring being formed with a diametrical cross bar 19'. Figs. 1, 2, 5 and 6 of the drawings, to which is attached an axially disposed stem 20, adapted to slide within the radial hole 18. A pin 20', passing through

the inner end of said stem 20, limits the outward movement thereof. The turret rim 6' is formed with a circumferential groove 21, in which the cross bars 19' of the rings 19 rest, as shown in Figs. 1, 2, 3 and 5 of the drawings. The inward movement of the ring 19 is limited by a series of adjustable stops 22 carried by the web of the turret 6, against which the inner ends of the stems 10 19 abut.

Supported by the upper part of the drum 4, in the path of travel of the grooves 17 in the turret rim 6', is a suitably constructed holder 23 adapted to contain a stack of ring liners 24. The lowermost liner of said stack normally rests upon the traveling surface of the turret rim 6', and is held in contact therewith by a weighted follower 25, Figs. 1 and 5 of the drawings, the lower surface 15 of which is formed with the same curvature as that of said rim 6'. The clearance between the exterior of the turret rim 6' and the interior of the drum 4 is less than the thickness of one ring liner, so that the lowermost of the series of liners 24 can not escape 20 from said holder 23 until one of the circular grooves 17 passes therebeneath.

The plunger rings 19, which during that 30 part of their travel lying above the axis of the turret are held by their own weight within their respective circular grooves 17, are so adjusted as to position by means of the stops 22, that their upper surfaces are below the surface of the rim 6' by a distance equal to 35 the thickness of one ring liner; that is, so that each groove 17 will contain but one ring liner. Therefore, when a groove 17 passes beneath the holder 23, the lowermost liner 24 therein drops into said groove, and is retained therein by the closely fitting drum 4, until the groove 17 reaches the lowest 40 point of its travel. At this point, indicated at A in Fig. 2, of the drawings, the plunger ring 19 is allowed to drop, by its own weight, 45 thus forcing the ring liner 24 into the flange 27 of a positioned can end 26, said end being advanced along the table 3 by a conveyer chain 28 provided with spaced upstanding lugs 29 for engaging the can ends 26. The 50 chain 28 is suitably supported and driven, as by means of an idler sprocket 30 and a driving sprocket 32 mounted upon the drive shaft 8. Guide rails 33 are provided on the table 3, on either side of the conveyer chain 28, to retain the moving can ends 26 in the 55 desired path.

The movement of the conveyer chain 28 and the rotation of the turret 6 are so timed that each can end 26 is correctly positioned at the point A, Fig. 2 of the drawings, to receive a ring liner 24 from a groove 17 in said turret 6. The can ends, after receiving the liners in the described manner, are carried on by the conveyer chain 8, and 60 removed from the machine in any suitable

manner, not shown in the drawings. The plunger rings 19 remain in their outer positions, as shown in Fig. 2 of the drawings, until they are again inverted by their circular travel, and fall back into their respective grooves 17 by the force of their own weight. 70

I am aware that changes may be made in the form and construction of the working parts of my device, without in any way affecting the principles involved, and I therefore do not wish to limit myself in this regard, but on the contrary I wish to claim the invention as broadly as I may. 75

Having thus described my invention, what 80 I claim as new and desire to protect by Letters Patent is:—

1. An apparatus for the described purpose, comprising a holder adapted to contain a stack of ring liners, means for engaging 85 circumferentially interiorly and exteriorly and removing a liner from said stack and applying the same to the flange of a continuously moving can end, and means for moving said can end. 90

2. An apparatus for the described purpose, comprising a holder adapted to contain a stack of ring liners, means for removing the lowermost liner of said stack within the holder and an ejector carried with said 95 removing means for applying the same to the flange of a continuously moving can end, and means for moving said can end and removing means continuously together while the ring liner is being so applied. 100

3. An apparatus for the described purpose, comprising a holder adapted to contain a stack of ring liners, and means for successively removing said liners in an axial direction from the holder and applying the same 105 to the flanges of positioned can ends, said removing means carrying an ejector for so applying the ring liners. 110

4. An apparatus for the described purpose, comprising a holder adapted to contain 110 a stack of ring liners, a movable ring liner container for successively removing said liners from the holder and carrying an ejector for applying the same to a succession of continuously moving can ends, and means 115 for moving said can ends.

5. An apparatus for the described purpose, comprising a holder adapted to contain a stack of ring liners, a rotary ring liner carrier to which the ring liners are successively transferred from said holder in a direction toward the axis of the carrier, and means for removing said ring liners in a direction away from the axis of the carrier. 120

6. An apparatus for the described purpose, comprising a holder adapted to contain a stack of ring liners, a rotary ring liner carrier to which the ring liners are successively transferred from said holder in a direction toward the axis of the carrier, and 125 130

- means for removing said ring liners in a direction away from the axis of the carrier, and a can end carrier which carries a succession of can ends in position to receive the ring liners so removed.
7. A rotary carrier for ring liners having on its peripheral side recesses for the reception of ring liners, means for inserting ring liners in said recesses in a direction which is radial inward relative to the axis of the carrier, and means for ejecting ring liners in an outward radial direction.
8. A rotary carrier for ring liners having on its peripheral side recesses for the reception of ring liners, means for inserting ring liners in said recesses in a direction which is radial inward relative to the axis of the carrier, and means for ejecting ring liners in an outward radial direction.
- 10 15 20 25 30 35 40 45 50 55 60 65 70 75 80 85 90 95 100 105 110 115 120 125 130
10. A rotary carrier for ring liners having recesses for the reception of ring liners and radially movable ejectors for expelling said liners, and means for inserting ring liners in said recesses, and combined therewith a can end carrier which presents can ends successively in alinement with the ring liners on said ring liner carrier to receive the ejected ring liners.
11. A rotary carrier for ring liners having recesses for the reception of the same and ejectors movable parallel with the plane of rotation of said carrier, and means for inserting ring liners in said recesses, and combined therewith a can end carrier which presents can ends successively in alinement with the ring liners on said ring liner carrier to receive the ejected ring liners.
12. A rotary carrier for ring liners having recesses for the reception of the same and ejectors movable parallel with the planes of rotation of said carrier, and means for inserting ring liners in said recesses.
13. An apparatus for the described purpose, the same comprising a continuously driven vertical rotatable member provided on the periphery thereof with a series of spaced ring liner seats, means for applying successively to said seats cut ring liners for the carrying thereof to an assembling position, means for successively delivering can ends to said assembling position and in axial alinement with the ring liners, and devices carried by said rotatable member near the seats for the ring liners for applying the same to the flanges of the positioned can ends and during the rotary movement of the carrier member.
14. In a machine for assembling can ends and paper ring liners, the combination of a continuously rotary carrier of ring-like form mounted to revolve on a substantially horizontal axis, means on said carrier arranged successively at equidistant points around the periphery thereof for holding and transporting successive ring liners, means for causing ring liners to be inserted in said holding means, means for assembling successive can ends in axial alinement with and at the outer sides of said ring liners while the latter are in and being carried by said holding means, and annular devices for forcing the ring liners radially outward and seating them in said alined can ends.
15. In a machine for assembling two classes of articles, namely shouldered can ends having ring liner seats and portions overhanging said seats, and paper ring liners adapted to fit in said seats and engage beneath said overhanging portions, the combination of a continuously rotary carrier of ring-like form mounted to revolve on a substantially horizontal axis, means on said carrier arranged successively at equidistant points around the periphery thereof for holding and transporting successively such ring liners, means for assembling successively such can ends in axial alinement with said ring liners while the latter are in and being carried by said holding means, and annular devices shaped to enter the seats of the can ends past and close to said overhanging portions for forcing the ring liners radially outward past said overhanging portions of and seating them in said alined can ends.
16. In a machine for assembling two classes of articles, namely shouldered can ends having ring liner seats at the outer sides of said shoulders and inwardly curled edges overhanging the outer parts of said seats, and paper ring liners of slightly greater diameter than said curled edges, the combination of a continuously rotary carrier of ring-like form mounted to revolve on a substantially horizontal axis, means on said carrier arranged successively at equidistant points around the periphery thereof for holding and transporting successively such ring liners, means for assembling successively such can ends in axial alinement with said ring liners while the latter are in and being carried by said holding means, and an annular ejecting device in each holding means of the carrier adapted to enter the seat of the alined can end between said curled edge and the shoulder thereof for forcing the ring liner radially outward past said curled edge and seating it in said alined can end.

17. An apparatus for the described purpose, comprising a holder adapted to contain a stack of ring liners, a rotating turret associated with said holder, said turret having a rim provided with an annular groove therein for removing the lowermost ring liner from said stack and carrying the same to a positioned can end, and devices for removing said liner from said groove and applying the same to the flange of said can end.

18. An apparatus for the described purpose, comprising a holder adapted to contain a stack of ring liners, a turret associated with said holder, said turret having a rim provided with an annular groove therein for removing the lowermost ring liner from said stack and carrying the same to a positioned can end, devices for removing said liner from said groove and applying the same to the flange of said can end, and means for imparting curvilinear motion to said turret.

19. An apparatus for the described purpose, comprising a holder adapted to contain a stack of ring liners, a turret associated with said holder, said turret having a rim provided with an annular groove therein for removing the lowermost ring liner from said stack and carrying the same to a continuously moving can end, devices for removing said liner from said groove and applying the same to the flange of said can end, and means for moving said turret and said can end in timed relation.

20. An apparatus for the described purpose, comprising a holder adapted to contain a stack of ring liners, a rotating turret associated with said holder, said turret having a rim provided with an annular groove therein for removing the lowermost ring liner from said stack and carrying the same to a positioned can end, means for retaining said liner in said groove, and devices associated with said turret for applying said liner to said can end.

21. An apparatus for the described purpose, comprising a holder adapted to contain a stack of ring liners, a rotating turret associated with said holder, said turret having a rim provided with an annular groove therein for removing the lowermost ring liner from the said stack and carrying the same to a positioned can end, a semi-cylindrical drum partially inclosing said turret for retaining said liner in said groove, devices associated with said turret for applying said liner to said can end, and interconnected mechanism for rotating said turret and positioning said can end.

22. An apparatus for the described purpose, comprising a holder adapted to contain a stack of ring liners, a turret associated with said holder, said turret having a rim provided with an annular groove therein for

removing the lowermost liner from said stack and carrying the same to a positioned can end, a freely shifting ring mounted within said groove for applying said liner to the flange of said can end, and interconnected mechanism for imparting rotary motion to said turret and for positioning said can end.

23. An apparatus for the described purpose, comprising a holder adapted to contain a stack of ring liners, a turret associated with said holder, said turret having a rim provided with an annular groove therein for removing the lowermost liner from said stack and carrying the same to a continuously moving can end, a freely shifting weighted ring mounted within said groove for applying said liner to the flange of said can end, and mechanism for rotating said turret and moving said can end in timed relation.

24. An apparatus for the described purpose, comprising a holder adapted to contain a stack of ring liners, a turret associated with said holder, said turret having a rim provided with an annular groove therein for removing the lowermost liner from said stack and carrying the same to a continuously moving can end, means for retaining said liner in said groove, a freely shifting weighted ring mounted within said groove for applying said liner to the flange of said can end, and mechanism for rotating said turret and moving said can end in timed relation.

25. An apparatus for the described purpose, comprising a holder adapted to contain a stack of ring liners, a turret associated with said holder, said turret having a rim provided with an annular groove therein for removing the lowermost liner from said stack and carrying the same to a continuously moving can end, a semicylindrical drum partially inclosing said turret for retaining said liner in said groove, a freely shifting weighted ring mounted within said groove for applying said liner to the flange of said can end, and mechanism for rotating said turret and moving said can end in timed relation.

26. In an apparatus for the described purpose, the combination of a carrier having recesses for receiving ring liners and holding them in said recesses by the friction of their edges, means at a receiving station for inserting ring liners in said recesses, means at an assembling station for holding can ends in axial alinement with the ring liners in said recesses, and means for removing the ring liners from the carrier and applying them to said can ends.

27. An apparatus for the described purpose, comprising a holder adapted to contain a stack of ring liners, and a movable member associated with said holder for remov-

ing the lowermost liner of said stack and having an annular ejector for applying the same to the flange of a positioned can end.

28. An apparatus for the described purpose, comprising a holder adapted to contain a stack of ring liners, and a movable member associated with said holder having a seat for receiving and removing the lowermost liner of said stack and having an annular ejector for applying the same to the flange of a positioned can end.

29. An apparatus for the described purpose, the same comprising a member having a curvilinear path of travel and provided with a plurality of peripherally disposed seats for securing, receiving and holding cut ring liners and conveying the same to an assembling position, mechanism for placing flanged can ends in substantial axial alignment with the ring liners carried by said member, and means for removing and applying the said liners radially from the axis of said member to the aligned can ends.

30. In a mechanism for assembling ring liners with can ends, in combination: a continuously rotatable member having successively arranged devices for circumferentially holding and carrying ring liners in a curvilinear path with the flat sides of such ring liners presented toward the convex side of said curvilinear path; means for successively causing ring liners to be inserted in said holding devices; means for alining can ends successively with said holding devices containing said liners and maintaining such alinement for the transfer of the liners; and radially movable ejectors on said continuously rotatable member for removing the liners from the said holding devices and seating them on the flanges of the said can ends.

31. In an apparatus for applying ring gaskets to the peripheral flanges of shouldered can covers for the production of interfolded hermetic seams with flanged can bodies, comprising a holder adapted to contain a stack of superposed previously formed ring gaskets, and means moving adjacent said stack for successively removing single ring gaskets therefrom and having annular ejecting means for applying the same to the peripheral flanges and around the shoulders of positioned can covers.

32. In an apparatus for applying ring gaskets to the peripheral flanges of shouldered can covers for the production of interfolded hermetic seams with flanged can bodies, comprising a holder adapted to contain a stack of superposed previously formed ring gaskets, means moving adjacent said stack for successively removing single ring gaskets from said stack and having ejecting means adapted to pass the shoulder of a can cover for applying the ring liners to the peripheral flanges and around the shoulders of

continuously advancing can covers, and means for continuously advancing said can covers.

33. In an apparatus for applying ring gaskets to the peripheral flanges of shouldered can covers for the production of interfolded hermetic seams with flanged can bodies, comprising a holder adapted to contain a stack of superposed previously formed ring gaskets, and means moving in a curvilinear path adjacent said stack for successively removing single ring gaskets therefrom and having ejecting means adapted to pass the shoulder of can covers for applying the ring liners to the peripheral flanges and around the shoulders of positioned can covers.

34. In an apparatus for applying ring gaskets to the peripheral flanges of shouldered can covers for the production of interfolded hermetic seams with flanged can bodies, comprising a holder adapted to contain a stack of previously formed ring gaskets in vertical superposed position, and curvilinear traveling means for successively removing the lowermost ring gasket from said stack, and having ejecting means adapted to pass the shoulders of can covers for successively applying the ring liners directly to the flanges and around the shoulders of successively positioned can covers.

35. In an apparatus for applying ring gaskets to the peripheral flanges of shouldered can covers for the production of interfolded hermetic seams with flanged can bodies, comprising a holder for a stack of superposed previously formed ring gaskets, a movable member having means for removing successively and conveying single ring gaskets from said stack, and a movable member having means for successively conveying flanged and shouldered can covers, the two said movable members moving in timed relation, whereby to bring said ring gaskets and said flanged and shouldered can ends into assembling relation, and means adapted to pass the shoulder of can covers acting to cause the said gaskets to pass around said shoulders and onto the flanges of said can covers.

36. In an apparatus for applying ring gaskets to shouldered can covers for the production of interfolded hermetic seams with can bodies, comprising a holder for a stack of superposed, individually separate, previously formed ring gaskets, a movable member for successively receiving and conveying in processional arrangement, single ring gaskets removed from said stack, and a movable member for successively receiving and conveying in processional arrangement shouldered can covers, the movement of said members being in such timed relation that ring gaskets and shouldered can covers are

successively brought into alinement, and ejecting means adapted to pass the shoulders of can covers whereby said gaskets and covers are assembled by passing the shoulders 5 of said can covers within the central openings of the said gaskets.

37. In an apparatus for assembling ring gaskets with shouldered can covers, for the production of interfolded hermetic seams 10 with can bodies, comprising a holder for a stack of superposed, individually separate, previously formed ring gaskets, means for successively separating single ring gaskets from said stack, and means for bringing 15 shouldered can covers and said separated ring gaskets into assembling relation, and ejecting means adapted to pass the shoulders of can covers for assembling said can covers with said ring gaskets by passing the 20 shoulders of said can covers within the central openings of said ring gaskets.

38. In an apparatus for assembling ring gaskets with shouldered can covers, for the production of interfolded, hermetic seams 25 with can bodies; comprising a holder for a stack of superposed, individually separate, previously formed ring gaskets, means for successively separating single ring gaskets from said stack, and means for bringing 30 shouldered can covers and said separated ring gaskets into assembling relation, including means adapted to pass the shoulders of can covers for assembling said can covers with said separated ring gaskets by 35 passing said gaskets over and around the shoulders of said can covers.

39. In a machine for applying previously formed can end ring liners to the flanges of shouldered can ends, for the production of 40 interfolded hermetic seams with flanged can bodies, in combination; continuously moving means for conveying previously formed can end ring liners, and continuously movable means for conveying shouldered can 45 ends, whereby said can ends and said can end liners are alined while being moved by said moving means, and ejecting means adapted to pass the shoulders of can ends for applying the ring liners on to the flanges 50 of the can ends.

40. In a machine for applying previously formed ring gaskets to the peripheral flanges of shouldered can covers for the production of interfolded hermetic seams with 55 flanged can bodies, in combination: continuously moving means for receiving and conveying such ring gaskets; continuously moving means for conveying shouldered can covers; and ejecting means adapted to pass 60 the shoulders of can covers; the two said

conveying means, moving to bring said ring gasket into alinement with said shouldered can cover and for said ejecting means to then pass said gasket from its conveying means onto the flange of the said shouldered 65 can end.

41. In a machine for applying previously formed ring gaskets to the peripheral flanges of shouldered can covers for the production of interfolded hermetic seams with flanged 70 can bodies, in combination: continuously moving means for conveying such ring gaskets; and means having provision for receiving and conveying shouldered can covers, the two said conveying means moving 75 in directions to successively bring ring gaskets and shouldered can covers into assembling relation, and ejecting means adapted to pass the shoulders of can covers for assembling the said ring gaskets and can covers while the conveyers are moving.

42. In a machine for applying previously formed ring gaskets to the flanges of shouldered can covers, for the production of interfolded hermetic seams with flanged can 85 bodies, in combination: two separate, co-acting, continuously moving means for respectively receiving and conveying previously formed ring gaskets and shouldered can covers, each from separate supplies, into 90 assembling relation, and ejecting means adapted to pass the shoulders of can covers for assembling the same ring gaskets and can covers while said two conveying means are moving.

43. In an apparatus for applying ring gaskets to the peripheral flanges of shouldered can covers for the production of interfolded hermetic seams with flanged can bodies, continuously moving means for provision for receiving and conveying previously formed ring gaskets, continuously moving means having provision for receiving and conveying shouldered can covers, the two said conveying means moving in directions to successively bring the ring gaskets and shouldered can ends into assembling relation, and ejecting means adapted to pass the shoulders of can covers for applying the said ring gaskets onto the peripheral flanges and around the shoulders of the said can covers.

In testimony whereof I have signed my name to this specification in the presence of two subscribing witnesses.

AXEL JOHNSON.
